UNITED STATES PATENT OFFICE

EDWARD N. CAVERT, OF CHICAGO, ILLINOIS, ASSIGNOR OF ONE-THIRD TO SAMUEL PETERSEN AND ONE-THIRD TO GEORGE B. ARCHER, BOTH OF CHICAGO, ILLINOIS

COMBINED DOCKING STALL AND BOAT BRAKE

Application filed October 17, 1930. Serial No. 489,319.

This invention relates to a combined docking stall and boat brake, and an object of the invention is the provision of an improved construction whereby the speed of a boat entering a docking stall may be rapidly retarded, and whereby a boat may be firmly engaged within the stall without the use of tying lines. The invention is particularly adapted to small power craft or other water craft where it is desirable or necessary to approach a landing pier at a relatively high speed and to rapidly reduce the speed; and the invention also provides improved means for maintaining a boat docked at a landing pier, which means is simple in construction and entirely under the control of the operator or pilot of the boat.

Other objects will appear hereinafter.

The invention consists in the combinations and arrangements of parts hereinafter described and claimed.

The invention will be best understood by reference to the accompanying drawings, forming a part of this specification and in which:

Fig. 1 is a plan view of a boat equipped with the present invention in docked position in a docking stall;

Fig. 2 is a cross-sectional view, taken substantially on the line 2—2 of Fig. 1;

Fig. 3 is a horizontal sectional view, taken substantially on the line 3—3 of Fig. 2;

Fig. 4 is a vertical sectional view, taken substantially on the line 4—4 of Fig. 1;

Fig. 5 is a detail sectional view, showing the mounting and connection of one of the braking shoes, taken substantially on the line 5—5 of Fig. 4;

Fig. 6 is a detail sectional view, taken substantially on the line 6—6 of Fig. 5;

Fig. 7 is an elevational view of the foot pedal control and release device, taken substantially on the line 7—7 of Fig. 3; and

Fig. 8 is a perspective view of one of the right braking or holding shoes.

As illustrated in the drawings, the preferred embodiment of the invention is shown in association with a landing pier 11 having a longitudinally extending beam 12 adapted to cooperate with the braking shoes mounted

upon one side of the boat. A guide bumper 13 having a guide beam 14 is disposed opposite the beam 12 and in spaced relation thereto to afford a docking stall for the boat 15. Beams 12 and 14 extend in parallel relation and are spaced apart a slightly greater distance than the greatest width of the boat to be received. The guide bumper may be supported by vertical standards 15 suitably secured by braces 17 to a cross member 18, which in turn is connected to the bracing 18' of the landing pier 11.

The braking and docking mechanism preferably comprises a pair of shoe members 19 and 20 mounted on the right side of the boat 15 and a corresponding pair of shoe members 21 and 22 mounted on the left side of the boat. These shoe members may be mounted on the upper surface of the deck as shown, or in any suitable place so as to be capable of a pivotal mounting and lateral extension or projection to engage the respective beams 12 and 14. In the preferred method of mounting shown, each of the shoe members 19 and 20 is keyed to a vertically extending pin 23 journaled in a bearing plate 24 secured to the deck 25. Below the plate 24, a block 26 is pinned to the shaft or pin 23 and is disposed on the opposite side of pivot pin 23 from the longitudinal center line of the boat. A cap 27 is arranged to be secured to block 26 by bolts 28, and block 26 and cap 27 are provided with complementary grooves to receive the right cable 29.

The pivot pin of shoe 20 carries a block 30 identical with block 26 and secured in the same manner to the cable 29. The rear extremity of cable 29 is connected to one end of a tension spring 31, the opposite end of which is connected to the frame of the boat. The effect of this construction and arrangement is normally to maintain the cable 29 in such position that the right hand shoes 19 and 20 are retracted so as not to extend beyond the side of the boat, or in the position of shoe 22 in Fig. 3. Cable 29 extends forwardly to pass under sheaves 32 and 33 mounted in suitable brackets, and then extends downwardly over sheave 34 for connection to arm 35 of foot pedal 36 which is

pivots mounted upon bracket 37 secured to the floor 38 adjacent the pilot's seat.

Shoes 21 and 22 are identical in mounting and arrangement with shoes 19 and 20 except to be in reverse position and mounted on the opposite side of the boat. Consequently, the blocks are likewise disposed outwardly from the pivot pins for connection to cable 39, the rear extremity of which is connected to tension spring 40 secured to the boat frame.

Cable 39 extends forwardly to pass under sheaves 41 and 42 and thence downwardly over sheave 43 for connection to arm 35. Thus it will be seen that upon depression of the foot pedal 36 for manual operation of the mechanism, the respective shoe members will be projected outwardly from the sides of the boat to engage the adjacent beams of the docking stall. For the purpose of maintaining the shoes in extended position, the foot pedal 36 may be provided with a pivoted locking pawl 44 for engagement with a toothed segment 45 on the upper surface of the bracket 37, locking pawl 44 being provided with a releasing extension 46. It will be noted that the engaging surfaces of the respective shoe members are curved so as to slidably engage the stall beams and offer sufficient frictional contact to bring the boat to a stop and also to maintain the boat in position while docked. For disengagement, it is merely necessary to depress the releasing projection 46 with the foot, whereupon tension springs 31 and 40 cause retraction of the respective shoe members through cables 29 and 39, and the boat is free to move out of the stall. The entire mechanism is always under the direct control of the pilot or operator by mere manipulation of the foot pedal 36 and releasing extension 46, without the necessity of leaving the boat. It will be apparent that any desired tension or stress may be exerted on the respective shoe members by means of the foot pedal 36. To facilitate entry and exit into and from a stall, the beams are preferably flared at the ends, as shown.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In combination, a boat, a docking stall having docking beam members spaced apart a distance greater than the width of said boat, a shoe member pivotally mounted adjacent one side of said boat constructed and

arranged when in extended position to engage one of said beam members for maintaining said boat in engaged position between said beam members, and manually operable means for moving said shoe member to extended position. 70

2. In combination, a boat, a docking stall having docking beam members spaced apart a distance greater than the width of said boat, a shoe member pivotally mounted adjacent one side of said boat constructed and arranged when in extended position to engage one of said beam members for maintaining said boat in engaged position between said beam members, manually operable 75 means for moving said shoe member to extended position, and resilient means arranged normally to maintain said shoe member in retracted position. 80

3. In combination, a boat, a docking stall having docking beam members spaced apart a distance greater than the width of said boat, a shoe member pivotally mounted adjacent one side of said boat constructed and arranged when in extended position to engage one of said beam members for maintaining said boat in engaged position between said beam members, an operating pedal, and a cable connecting said pedal and said shoe member whereby said shoe member will be moved to extended position upon operation of said pedal. 85

4. In combination, a boat, a docking stall having docking beam members spaced apart a distance greater than the width of said boat, a shoe member pivotally mounted adjacent one side of said boat constructed and arranged when in extended position to engage one of said beam members for maintaining said boat in engaged position between 90 said beam members, an operating pedal, a cable connecting said pedal and said shoe member whereby said shoe member will be moved to extended position upon operation of said pedal, and resilient means arranged 95 normally to maintain said shoe member in retracted position. 100

5. In combination, a boat, a docking stall having docking beam members spaced apart a distance greater than the width of said boat, a shoe member pivotally mounted adjacent the right side of said boat, a shoe member pivotally mounted adjacent the left side of said boat, said shoe members constructed and arranged when in extended position to engage 105 said respective beam members, and means for moving said shoe members into extended position. 110

6. In combination, a boat, a docking stall having docking beam members spaced apart 115 a distance greater than the width of said boat, a shoe member pivotally mounted adjacent the right side of said boat, a shoe member pivotally mounted adjacent the left side of said boat, said shoe members con- 120

structed and arranged when in extended position to engage said respective beam members, means for moving said shoe members into extended position, and means arranged normally to maintain said shoe members in retracted position.

7. In combination, a boat, a docking stall having docking beam members spaced apart a distance greater than the width of said boat, a shoe member pivotally mounted adjacent the right side of said boat, a shoe member pivotally mounted adjacent the left side of said boat, said shoe members constructed and arranged when in extended position to engage said respective beam members, an operating pedal, a cable connecting said right shoe member and said pedal, and a second cable connecting said left shoe member and said pedal, whereby upon operation of said pedal said shoe members will be moved in unison into extended position.

8. In combination, a boat, a docking stall having docking beam members spaced apart a distance greater than the width of said boat, a shoe member pivotally mounted adjacent the right side of said boat, a shoe member pivotally mounted adjacent the left side of said boat, said shoe members constructed and arranged when in extended position to engage said respective beam members, an operating pedal, a cable connecting said right shoe member and said pedal, a second cable connecting said left shoe member and said pedal, whereby upon operation of said pedal said shoe members will be moved in unison into extended position, and means arranged normally to maintain said shoe members in retracted position.

9. In combination, a boat, a docking stall having docking beam members spaced apart a distance greater than the width of said boat, a shoe member pivotally mounted adjacent the right side of said boat, a shoe member pivotally mounted adjacent the left side of said boat, said shoe members constructed and arranged when in extended position to engage said respective beam members, an operating pedal, a cable connecting said right shoe member and said pedal, a second cable connecting said left shoe member and said pedal, whereby upon operation of said pedal said shoe members will be moved in unison into extended position, and a locking member for holding said pedal in a selected operative position.

10. In combination, a boat, a docking stall having docking beam members spaced apart a distance greater than the width of said boat, a shoe member pivotally mounted adjacent the right side of said boat, a shoe member pivotally mounted adjacent the left side of said boat, said shoe members constructed and arranged when in extended position to engage said respective beam members, an operating pedal, a cable connecting said right

shoe member and said pedal, a second cable connecting said left shoe member and said pedal, whereby upon operation of said pedal said shoe members will be moved in unison into extended position, and spring means connected to said cables and arranged normally to maintain said shoe members in retracted position.

In testimony whereof I have signed my name to this specification.

EDWARD N. CAVERT.
